UNITED STATES PATENT OFFICE.

IRVIN H. PLEUKHARP, OF COLUMBUS, OHIO.

SPEED-CHANGING AND TRANSMISSION GEAR.

SPECIFICATION forming part of Reissued Letters Patent No. 12,369, dated July 11, 1905.

Original No. 767,238, dated August 9, 1904. Application for reissue filed May 10, 1905. Serial No. 259,838.

To all whom it may concern:

Be it known that I, IRVIN H. PLEUKHARP, a resident of Columbus, in the county of Franklin and State of Ohio, have invented certain new and useful Improvements in Speed-Changing and Transmission Gear; and I do hereby declare the following to be a full, clear, and exact description of the invention, such as will enable others skilled in the art to which it applies to make and use the same:

The object of this invention is to provide a speed - changing and reversing transmission gear of simple, strong, and economical construction and having a direct drive.

15 The invention is embodied in the construction hereinafter described and claimed.

In the accompanying drawings, illustrating one embodiment only of the invention, Figure 1 is a sectional view through the gearing on a plane passing through the axes of the driving and driven shafts or shaft and axle, the shaft and axle not themselves, however, being shown in section. Fig. 2 is a section on the plane $\alpha\alpha$, Fig. 1, looking toward the left. Fig. 3 is a side view on a smaller scale, a portion being broken out to show the ring-clutch-shifting device. Fig. 4 is a diagrammatic fragmentary view showing the driving-disks and ring-clutch therefor. Fig. 5 is a sectional view of the speed-changing clutch or the clutch of the driving-shaft. Fig. 6 is a diagram illustrating the peculiar construction of the teeth of the clutch of the driving-shaft.

Where the driven shaft is the axle of a motor-vehicle or automobile, it will preferably be composed of two parts 1 and 1¹. These will have their abutting ends provided with a compensating gear permitting one part to move faster than the other and consisting in the instance shown of circular-toothed gears 2 and 2¹, keyed on the ends of the shafts and facing each other, and one or more pinions 3, meshing with the gears 2 and 2¹, mounted in a collar 4 between said gears. The compensating gearing is inclosed or boxed by heads 5 and 5¹ and a cylinder-housing ring 6 between said heads, the spindles of the pinions 3 being passed through said cylinder and engaging it, so that if the cylinder be turned the axles 1 and 1¹ will also be turned. Mounted loosely

on the cylinder or box inclosing the compensating gear are two large disks 7 and 7¹, the former shown to have three rows 8, 8¹, and 8² of radial face-teeth located in concentric circles and the latter having a single row 8³ of such teeth located opposite and parallel to the outermost row 8² on the disk 7.

9 designates the driving-shaft operated by the engine or motor. Arranged beyond the end of this and suitably hung or supported between the disks 7 and 7¹ are three concentric shafts 10, 11, and 12, having at their inner ends pinions 10¹, 11¹, and 12¹, respectively, meshing with the two rows of teeth 8, 8¹ and the two rows 8² and 8³, respectively. The outer ends of the concentric shafts 10, 11, and 12 are flanged to the same diameter, as seen at 10^b, 11^b, and 12^b, and the peripheries of said flanges are toothed. The end of the driving-shaft is furnished with a slip sleeve or clutch 13, feather-keyed thereon, and said sleeve is furnished at its inner end with a flange internally toothed to engage with the teeth of the flanges 10^b, 11^b, and 12^b. The flanges 10^b, 11^b, and 12^b are spaced apart sufficiently to permit the teeth proper of the clutch 13 to pass between them without engaging the teeth of two flanges at the same time. The teeth of the clutch, and also, if desired, the teeth of the flanges, are preferably wedge-shaped at each side, as depicted in Fig. 6, to facilitate their entrance between each other. To further facilitate their entrance and the guidance of the teeth into mesh with each other, several of them can be provided with steel points, preferably flexible, set in staggered or irregular arrangement with respect to each other.

14 designates the reversing-ring clutch. This consists of a thick band of metal fitting around the cylinder or housing ring 6 and keyed thereon by keys 14¹, that prevent concentric movement thereof with respect to the housing 6, but permit lateral movement thereof. The reversing-clutch is toothed on its opposite edges, as seen in Fig. 5, and the adjacent walls of the disks 7 and 7¹ are correspondingly toothed. The reversing-ring can of course be slid laterally to engage the corresponding teeth of one or the other of the disks 7 and 7¹, but not both at the same time.

time, and this ring is made with a peripheral groove, into which extends the crank end of a shifting rod 15. The clutch 13 also is provided with an appropriate shifting device 13^a.

5 The disks 7 and 7^a are inclosed in a suitable housing and preferably so that they can run in oil.

The operation is as follows: The direction of motion of the driving-shaft 9 and clutch 13 is always the same. If the clutch-ring 14 be engaged by the disk 7, three different speeds of the axle 1 and 1^a in one direction—for example, the forward direction—can be obtained by shifting the clutch 13 outward. By shifting the clutch farther outward the clutch 13 runs free and transmits no motion to the axle. By shifting the clutches 14 and 13 into the position seen in Fig. 1 the motion of the axle is reversed, because the disk 7^a becomes connected with the differential-gear housing.

The forms and proportions of the parts can be varied without departing from the essence of the invention.

The disk 7^a can of course be provided with 25 three rows of concentric teeth instead of one.

Having fully described my invention, what I claim as new, and desire to secure by Letters Patent, is—

1. The combination with a driven shaft, two 30 disks thereon normally loose with respect thereto, means for locking either of said disks to the driven shaft, several annular series of gear-teeth on one disk, pinions meshing therewith, an annular series of gear-teeth on the 35 other disk meshing with one of said pinions, a drive-shaft and means for locking any one of said pinions to turn therewith.

2. The combination with a driven shaft, two 40 disks thereon normally loose with respect thereto, means for locking either of said disks to the driven shaft, several annular series of gear-teeth on one disk, an annular series of gear-teeth on the other disk opposite to and facing one of the annular series of teeth on 45 the other disk, a pinion meshing with the facing teeth on both disks, pinions meshing with the other series of teeth on the disk, a drive-shaft and means on the drive-shaft constructed to lock any of the pinions to turn there- 50 with.

3. In a power-transmission mechanism, the combination of a driven shaft, two disks thereon and normally loose with respect thereto and one of them having concentric rows of 55 gear-teeth, the other disk having an annular series of teeth, a movable clutch to connect either of said disks with said shaft, concentric shafts, pinions thereon to engage the teeth of the disks, a driving-shaft, and a clutch 60 thereon movable to connect any of said pinions rotatively therewith.

4. In a power-transmission mechanism, the

combination with a two-part driven shaft or axle, a differential gearing connecting them, and a housing therefor, of two disks normally 65 loose on said housing, one disk having concentric rows of gear-teeth and the other disk having an annular series of teeth, a clutch to connect either of said disks with said housing, concentric shafts, pinions thereon to engage 70 the teeth of the disks, a driving-shaft, and a clutch thereon movable to operatively connect any of said pinions with said driving-shaft.

5. In a power-transmission mechanism, the combination with a two-part driven shaft or 75 axle, a differential gearing connecting them comprising gears 2 and 2^a keyed thereon and a pinion or pinions 3 between and engaging them, a housing-ring connected with said pinions, two disks loose on said housing-ring one 80 having concentric rows of teeth, the other disk having an annular series of teeth a clutching-ring connected with said housing-ring adapted to be slid laterally to engage either of said disks and connect it operatively with the housing-ring, concentric shafts bearing pinions to 85 engage the teeth of the disks, a driving-shaft and sliding clutch thereon adapted to operatively connect any of said pinions with said driving-shaft.

6. In a power-transmission mechanism, the combination with a two-part driven shaft or axle, a differential gearing connecting them comprising gears 2 and 2^a keyed thereon and a pinion or pinions 3 between and engaging 95 them, a housing-ring connected with said pinions, two disks loose on said housing-ring one having concentric rows of gear-teeth, the other disk having an annular series of teeth and both having clutching-teeth, a clutching-ring having 100 its edges toothed to engage the clutching-teeth of the disks and connected with said housing-ring so as to be movable laterally theron and connect operatively either of the disks with the housing-ring, concentric shafts bearing pinions to engage the teeth of the disks, a driving-shaft and sliding clutch thereon adapted to operatively connect any of said pinions with said driving-shaft.

7. A transmission-gearing having meshing gears provided with teeth having wedge-shaped 110 edges and an elastic guiding-finger on one or more of the teeth.

8. In a transmission-gearing, meshing gears provided with teeth having wedge-shaped 115 edges and elastic fingers on said teeth differently located as regards their position with respect to the body of the tooth.

In testimony whereof I affix my signature in the presence of two witnesses.

IRVIN H. PLEUKHARP.
